BURT NEULON PIERCE, OF INDIANAPOLIS, INDIANA.

CARBURETER.

No. 917,125.

Specification of Letters Patent.

Patented April 6, 1909.

Application filed January 24, 1907. Serial No. 353,773.

To all whom it may concern:

Be it known that I, BURT NEULON PIERCE, of Indianapolis, county of Marion, and State of Indiana, have invented a certain new and useful Carbureter; and I do hereby declare that the following is a full, clear, and exact description thereof, reference being had to the accompanying drawings, in which like numerals refer to like parts.

10 The object of this invention is to provide an improved carbureter for combustion engines, one feature of which consists in uniting the outlet end with a shell of the carbureter so that the carbureter can be connected with a vertical or horizontal pipe or to pipes leading in two directions to the engine cylinder without modifying the position of the carbureter.

Another and a more important feature 20 consists in providing means in connection with an air inlet valve for opening the fuel inlet valve simultaneously and to a proportionate extent as the air inlet valve is opened in order to bring about a proportionate admixture of fuel and air to form the ultimate gas in the engine. Also in connection with the foregoing, of a positively acting spring, which will always close the air inlet valve and, consequently, the fuel inlet valve when 30 not acted upon by the suction of the piston of the engine. And such closing action is perfectly free and independent of all other influences. One result of this arrangement is that this carbureter does not have to be 35 maintained in any certain position. It can be inverted and act with the same regularity as if held upright. Another effect of such construction is that the carbureter needs no float or float chamber filled with an accumulation of gasoline or other fuel to be 40 maintained in a certain position. In connection with the foregoing the throttle lever tends to regulate both the air inlet valve and the fuel inlet valve by limiting the opening 45 of the air inlet valve only.

Another important feature consists in providing an emergency air inlet valve in addition to the regular air inlet valve, and held closed by a stronger spring than the regular 50 air inlet valve so that a sufficient quantity of air will always be supplied to the carbureter to satisfy the suction of the pistons and prevent a vacuum in the cylinder of the engine. This emergency air inlet valve also 55 admits air directly to the cylinder while the air is in a cool state and even after the regu-

lar air inlet valve has been closed by the throttle. Another effect is of a regulative character, for when the air enters through the emergency or secondary air inlet valve, 60 the suction effect of the piston upon the fuel inlet is thereby relatively diminished.

Another feature consists in the waste opening in the carbureter whereby the same may be kept clean, it being placed to one 65 side of the partition so that it does not interfere with the intake of the air and fuel in the shell of the carbureter and near a small opening through the lower part of the partition through which fluid in the shell may 70 pass out through the waste opening.

In the drawings Figure 1 is a central vertical section through the carbureter with the parts in their normal operating position, the outlet end thereof being arranged so as to 75 connect with a vertical pipe. Fig. 2 is a section on the line 2—2 of Fig. 1. Fig. 3 is the same as Fig. 1 with both valves open and the outlet end turned and in position to be connected with a horizontal pipe. Fig. 4 80 is a section on the line 4—4 of Fig. 1.

In detail the carbureter shell 10 has an integral air inlet end 11 adapted to be connected with a pipe, and an adjustable outlet end 12. The parts 10 and 12 are connected by bolts 13, and at their junction are both cut diagonally on the line 45° from the normal vertical or horizontal lines through the outlet portion of the body 10 and through the outlet end 12. This feature of 85 the construction enables the outlet end of the carbureter to be connected with a vertical or horizontal pipe leading to the cylinder of the gas engine, or to adjust it in at least two positions. 95

The fuel enters the shell of the carbureter through a removable casing 15, which is screwed into a sleeve 116 that extends downwardly from the shell of the carbureter. The outlet end of the casing 15 is closed by 100 a valve 16 on the stem 17 that protrudes through the outlet opening. The valve is forced against its seat by a spring 18 coiled spirally about the stem thereof below the valve 16. This valve mechanism is held in 105 place from escape by a lock-nut 19. In the shell 10 there is a partition 20 which forms two chambers 21 and 22. The chamber 21 is on the air side of the partition, and the chamber 22 is on the fuel inlet side thereof, 110 and the chamber 22 is the mixing chamber for the air and fuel. This partition has two

openings in it, the lower opening 23 being opposite to the air inlet end 11 and being closed by a disk valve 24 that is carried on a slightly conical tubular sleeve 25 that is mounted on a rod 26 which is threaded at both ends, the inner end screwing into an arm 27 that extends from the shell 10 on the air side of the partition 20, and the other end extending through the packing 10 28 and having on it a lock-nut 29.

A spring 30 is wound spirally about the rod 26 and presses against the sleeve 25 at one end and the packing 28 at the other, so that it tends to keep the valve 24 closed. 15 The tapering sleeve 25 is in engagement with the upper end of the valve stem 17 so that when the valve 24 is opened and moved to the right, as appears in Fig. 1, the sleeve 29 will force down the stem 17 and at the 20 same time open the fuel inlet valve 16. The greater the opening movement of the valve 24, the greater will be the opening movement of the valve 16, so that there is co-operation between these two valves controlled by the valve 24. The opening movement of the valve 24 is ultimately stopped or limited by a buffer 31 on a throttle arm 25 32 that is operated by a lever 33.

The upper opening 40 in the partition 20 30 is substantially the same in shape and diameter as the lower opening 23, and is closed by a substantially similar disk valve 41, which is slidably mounted on the valve stem or rod 42 that is threaded or screws 35 into a bearing 43 on the shell 10 and is locked in place by a nut 44 and has a pin 45, whereby the said rod 42 may be adjusted into position. The inner end of the 40 valve rod 42 has on it a head 46, and there is a spring 47 mounted on said rod between the valve 41 and the head 46.

An important feature of the invention consists in the fact that the spring 47 which actuates and holds closed the upper valve 45 41, is stronger and has greater tension than the spring 30 that holds the lower valve 24 seated. The effect of this variation in tension of the springs is to cause the lower valve to open normally instead of the upper valve, and the upper valve 41 will open 50 only in emergencies, as will hereafter be explained.

There is an opening 50 in the lower part of the partition 20, as appears in Figs. 1 55 and 2, having considerable width, as appears in the last figure. There is also a pair of passageways 51 extending through the nut 52 that is threaded in the casing 15, and in which the lower end of the valve 60 stem 17 moves and against which the lower end of the spring 18 acts. These holes 51 communicate with the small chamber around the valve stem and within the casing 15, and in this way the fuel is admitted 65 to the casing 15, and subsequently to the

chamber 22 in the shell 10. There is also a drain outlet 53 leading from the bottom of the shell 10, especially from the lower part of the chamber 21 on the air side of the partition 20. By being located on the air 70 side of the partition 20, this drain does not interfere with the operation of the device, and by reason of the opening 50 in the partition being adjacent said drain opening, it is easy to drain the carburetor. 75

The operation of this carburetor is as follows: The suction in the cylinder of the gas engine opens the valve 24, and its tapering sleeve 25 opens the valve 16, and then air and fuel are both drawn into the chamber 80 22 at the same moment, and thence passes from the outlet end to the cylinder of the engine. The admission of fuel and air is regulated by the throttle lever 33, arm 32 and buffer 31, which limits the extent of the 85 opening movement of the valve 24, and that through the tapering sleeve 25 correspondingly limits the extent of the opening movement of the valve 16 for the admission of fuel. 90

To prevent a vacuum occurring in the cylinder by reason of an insufficient quantity of air, the upper valve 41 is provided in this carburetor so as to admit an increased volume of air to the carburetor, but this does not occur excepting when the suction is sufficiently great to draw the lower valve 24 to its limit and also overcome the tension of the spring 47 that acts on the upper valve 41. Ordinarily this upper valve 41 would not operate, the lower valve 24 admitting a sufficient volume of air, and said lower valve would normally open because its spring is weaker than the spring that acts on the upper valve. 100

What I claim as my invention and desire to secure by Letters Patent is:

1. A carburetor including a shell, a rod adjustably mounted therein, an air inlet valve slidably mounted on said rod, a tapering sleeve on said rod and movable by said air inlet valve, a spring on said rod that tends to move said air inlet valve and sleeve to the closing position, and a spring-pressed fuel inlet valve with the stem in engagement 110 with said tapering sleeve and extending at substantially a right angle from said rod, substantially as set forth.

2. A carburetor including a shell, a rod adjustably mounted therein, an air inlet valve 120 slidably mounted on said rod, a tapering sleeve on said rod and movable by said air inlet valve, a spring on said rod that tends to move said air inlet valve and sleeve to the closing position, a spring-pressed fuel inlet valve with the stem in engagement 125 with said tapering sleeve and extending at substantially a right angle from said rod, a shaft extending into said shell with a throttle arm on the inner end thereof, a buffer on 130

the end of said arm to engage said inlet valve and limit its throw, and means outside of the carbureter for operating said shaft.

3. A carbureter including a pair of air inlet valves, springs for seating said valves, one valve nearer the outlet end of the shell and having a stronger spring than the spring that acts against the more remote air inlet valve, a fuel inlet valve, and means 10 moved directly by the air inlet valve that is more remote from the outlet opening from the shell for opening said fuel inlet valve whereby when the air inlet valve nearer the outlet opening from the shell is open, the 15 suction of the engine piston on the fuel inlet will be correspondingly diminished.

4. A carbureter including a shell having an air inlet opening, an outlet opening, a partition in said shell between the inlet and 20 outlet openings, said partition having air inlet openings opposite the air inlet opening of the shell, an air inlet valve for closing each air inlet opening in said partition

one of said valves being nearer the outlet opening than the other valve, a spring for 25 holding each of said air inlet valves closed, the spring for the valve nearer the outlet opening in the shell being stronger than the spring for the other valve, a fuel inlet valve, means adjacent and moved by said air valve 30 that is remote from the outlet opening from the shell for directly opening said fuel inlet valve.

5. A carbureter including a shell, a partition dividing the air inlet side from the fuel 35 inlet side of the interior of the shell, said partition having an opening at its lower end, and a waste outlet through the bottom of the shell on the air side of said partition.

In witness whereof, I have hereunto af- 40 fixed my signature in the presence of the witnesses herein named.

BURT NEULON PIERCE.
